BATTERY CASE

Frank S. Flider, Chicago, Ill., assignor to The Justrite
Manufacturing Company, Chicago, Ill.

Filed Dec. 14, 1970, Ser. No. 26,496

Term of patent 14 years

Int. Cl. D13—02

U.S. Cl. D26—6

FIG.1

FIG.2

FIG.6

FIG.4

FIG.3

FIG.5

FIG.8

FIG.7

FIG. 9

FIG. 10

FIG. 11

FIG. 12

FIG. 1 is a perspective view looking at the front top of the battery case showing my new design;

FIG. 2 is a perspective rear bottom view of the battery case;

FIG. 3 is a bottom plan view of the battery case, positioned as it would be in actual use when clipped to a belt or the like;

FIG. 4 is the front plan view of the battery case positioned as in FIG. 3;

FIG. 5 is a rear plan view of the battery case;

FIG. 6 is a left side view of the battery case;

FIG. 7 is the right side view of the battery case;

FIG. 8 is a bottom plan view of the battery case;

FIG. 9 is a perspective view of the battery case in the open position;

FIG. 10 is a top plan view of the battery case in the open position;

FIG. 11 is a right side view of the battery case in the open position; and

FIG. 12 is a front view of the battery case in the open position.

I claim:

The ornamental design for a battery case, as shown and described.
